CLOSURE LOCK AND ACTUATING MECHANISM

Edward Kressbach, Milwaukee, Wis.

Application March 10, 1947, Serial No. 733,457

6 Claims. (Cl. 268—44)

1

My present invention relates generally to improvements in the art of closures and relates more particularly to improvements in the construction and operation of closure locks and actuating mechanisms.

A primary object of the present invention is to provide an improved closure lock and actuating mechanism which is simple, compact, and durable in construction, and which is moreover highly efficient and practical in actual use.

It is a more specific object of this invention to provide an improved closure actuating mechanism which is adapted to be readily locked by means of a tumbler lock and in which the closure may still be opened and closed in the event the key is broken while in the lock.

Another specific object of the invention is to provide an improved closure lock and actuating mechanism wherein a toggle is employed for positively preventing movement of the closure by prying or the like.

Another specific object of my invention is to provide an improved and highly efficient closure actuating mechanism which is silent in operation and especially adapted for use in church tabernacles and the like and in localities where noise is objectionable.

A further specific object of my present invention is to provide an improved closure actuating mechanism which is adapted to permit positive opening and closing of the closure without the use of toothed gearing.

An additional specific object of the present invention is to provide an improved closure lock and actuating mechanism which comprises relatively few simple parts which may be readily adjusted to insure proper opening and closing.

Still another specific object of the present invention is to provide an improved closure lock and actuating mechanism which has many adaptations, which may be readily manufactured and installed at moderate cost, and wherein all parts are easily accessible for repair or replacement.

These and other specific objects and advantages of the present invention will be apparent from the following detailed description.

A clear conception of the several features constituting my present improvement, and of the mode of constructing and of utilizing closures provided with locks and actuating mechanisms embodying my invention, may be had by referring to the drawings accompanying and forming a part of this specification, wherein like refer-

2

ence characters designate the same or similar parts in the various views.

Fig. 1 is a bottom view of a closure lock and actuating mechanism embodying my invention, showing the parts in locking position;

Fig. 2 is a part sectional fragmentary front view of the assemblage showing the closure locked in closed position, a section having been taken transversely through the lock along the line 2—2 of Fig. 1;

Fig. 3 is a bottom view of the mechanism showing the closure in open position;

Fig. 4 is a part sectional fragmentary front view showing the closure open and with the lock in elevation as applied to a fragment of the casing; and

Fig. 5 is a side view of the special releasing and latching bar adapted for use with my improved mechanism.

While the invention has been shown and described as being particularly applicable to closures of a particular type mounted for sliding arcuate movement about a central pivot, it is not my desire or intention to unnecessarily limit the scope or utility of the improvement by virtue of such embodiment.

Referring to the drawings, the typical assemblage shown therein as embodying the improvement comprises, in general, a tabernacle casing 30 or wall 10 of substantially cylindrical shape and having an opening 41 adapted to be closed by a door or closure 12; a bottom plate 13 secured in suitable fashion to an end of the casing 10; a base plate 14 spaced from the bottom plate 13 and supported by means of columns or posts 15, 15', the plate 14 thereby forming the tabernacle floor and providing a housing for the improved closure lock and actuating mechanism; a tumbler lock 16 of the Yale type secured in position below the base plate 14 by means of a mounting bracket or plate 17 or the like attached to the plate 14 by screws 18; a substantially flat bracket 19 or the like mounted to swing on an anti-friction bearing 20 secured to the bottom of the base plate 14, the bracket 19 carrying the closure 12 at its swinging end so as to permit arcuate swinging movement of the closure 12 about the periphery of the plate 14; a toggle arm or lever 21 having one end thereof rigidly secured, as by screws 22, to the revolvable hub 23 of the lock 16 and the swinging end thereof loosely pivotally attached to one end of a toggle link or member 24; a motion transfer lever 25 fixedly pivoted to the bottom of the plate 14 at 26 and having one end thereof loosely pivotally con-

connected to the toggle arm or link 24 and its opposite end pivotally connected to a link 27, the opposite end of which is pivotally connected to the closure carrying bracket 19 at 28 intermediate the bearing 20 and closure 12; a depending projection 29 carried by the bracket 19 near the closure 12 and cooperable with a fixed stop 30 secured in a suitable manner to the plate 17 or the base 14 adjacent the lock hub 23; and a latch hook 31 carried by the lock hub 23 and projecting laterally therefrom and adapted to engage the projection 29 upon rotation of the hub 23, the hooked element or latch 31 being provided with a headed pin 32 extending outwardly therefrom for reasons to be hereinafter more fully described.

The lock 16 is of the usual well-known construction and the lock casing 33, which is secured to the plate or bracket 17, carries the tumblers 34 which are actuated upon insertion of the key 35 to release the usual revolving plug which carries the hub 23 on a square shaft 36, thereby providing for rotation of the hub 23 with the revolving plug upon turning of the key 35 within the lock. To positively stop rotation of the hub 23 and its associated parts in locked position as shown in Figs. 1 and 2, a laterally projecting stop pin 37 adapted to coact with a depending portion of the plate 17 may be provided; and reverse rotation of the hub 23 may be positively stopped by proper placement of the supporting column 15' so as to coact with one edge of the plate 19 upon opening swinging movement thereof through its toggle and link connections with the hub 23, as will be hereinafter more clearly described, to the position shown in Figs. 3 and 4.

To provide for proper adjustment of the closure actuating mechanism, the toggle member 24 may be provided with screw threads extending to the opposite ends thereof and coacting with the internally threaded pivot sockets 38 which may be clamped in adjusted position on the member 24 by means of lock nuts 39, and the link 27 may likewise be provided with screw threads adapted to coact with the associated internally threaded pivot sockets 40 which may be clamped in adjusted position in like fashion by means of lock nuts 41. Adjustments in the length of either the member 24 or the link 27 may be readily effected in an obvious manner by first detaching either end of the member 24 or link 27 from its associated element 21, 25, or 19 as the case may be, thereafter backing the lock nut 39 or 41 away from its adjacent socket 38 or 40, next screwing the socket 38 or 40 on the threaded member 24 or link 27 in the desired direction, and finally returning the lock nut to locking position adjacent the adjusted socket and effecting attachment of the member 24 or link 27 to the element 21, 25, or 19 from which it was detached.

The closure 12 may be readily unlocked and swung from closed and locked position shown in Figs. 1 and 2 to open position shown in Figs. 3 and 4 by merely inserting the key 35 within the lock 16 and rotating the same clockwise. Insertion of the key 35 within the lock 16 moves the tumblers 34 so as to permit rotation of the usual revolvable plug within the lock casing 33, and clockwise movement of the key rotates this plug and the square shaft 36 and the hub 23 carried thereby. Since the latch hook 31 and toggle lever 21 are both rigidly secured to or formed integral with the hub 23, clockwise rotation of

the hub 23 causes the latch 31 to swing out of engagement with the projection 29 to unlock the closure and causes the toggle lever 21 to simultaneously swing downwardly moving the lever 21 and its connection 24 across the toggle axis, thereby swinging the bracket 19 on its bearing 20, through the connecting toggle member 24, motion transfer lever 25, and link 27, toward the position shown in Figs. 3 and 4. As the bracket 19 is thus actuated, the closure 12 carried thereby is arcuately swung to open position, movement of the entire mechanism being positively stopped with the closure 12 in open position upon contact of the bracket 19 with the column 15'.

To effect closing and locking of the closure or door 12, it is merely necessary to rotate the key 35 counterclockwise and thereafter withdraw the same from the lock 16. Upon such counterclockwise movement of the key 35, the toggle lever 21 is swung upwardly toward the base plate 14, the lever 21 and its connection 24 being moved across the toggle axis, thereby causing the closure carrying bracket 19, by reason of the connecting elements 24, 25, and 27, to swing toward the lock 16 and the position shown in Figs. 1 and 2. Simultaneously, the latch 31 is swung upwardly and into hooked engagement with the projection 29, as shown in Figs. 1 and 2, after the projection 29 reaches the stop 30. When the mechanism is in such door closed position, the stop pin 37 on the hub 23 is in positive contact with the depending edge of the bracket 17, and upon withdrawal of the key 35, final locking is effected.

Should the key 35 break while in the lock 16, it would normally not be possible to effect actuation and latching of the closure 12 until after repairs have been made. However, I have provided means whereby the closure may still be opened and closed, as well as latched and unlatched, as long as the lock tumblers 34 are in such position as will permit rotation of the hub 23 and square shaft 36. As hereinabove set forth, I provide the latch 31 with a headed pin 32 extending outwardly therefrom; and I additionally provide a through opening or aperture screw-threaded to receive a closure screw 42 in the casing wall 10 adjacent the lock 16 and in the vicinity of the latch 31, and a slightly hooked elongated bar 43 which may be readily utilized to release and latch the mechanism in such emergencies before repair of the lock may be effected.

If the key 35 is broken off in the lock 16 with the tumblers in such position as will permit rotation of the usual revolvable plug, square shaft 36 and hub 23 and it is desired to latch or unlatch the closure 12 and to actuate the same, the screw 42 may be readily removed from the aperture in the casing wall, and the hooked end of the bar 43 may then be inserted through this aperture and into engagement with the headed pin 32 carried by the latch 31. With the bar 43 serving as a lever fulcrum in the casing 10, the latch 31 may then be swung into or out of engagement with the projection 29 to effect latching or unlatching of the mechanism in an obvious manner, thereby preventing or permitting opening of the closure 12 as the case may be, and this procedure may be repeated as often as necessary until repairs have been made to the lock 16.

From the foregoing detailed description, it will be apparent that my present invention provides a simple, durable, and compact locking and actuating mechanism for closures, all parts of which

may be readily manufactured and quickly assembled at low cost. The improved mechanism has proven highly efficient and practical in actual use as applied to church tabernacles, and may obviously be readily utilized in other instances as applied to doors and closures. Employment of the toggle lever 21 and its associated parts, including the link 24, lever 25, link 27 and bracket 19, eliminates the need of employing expensive toothed gearing, and furthermore provides an inexpensive mechanism wherein movement of the closure by prying or the like is positively prevented. The closure actuating mechanism is especially applicable and particularly advantageous for use in localities where noise is objectionable since it is silent in operation, and positive opening or closing of the closure 12 is permitted and effected by one simple operation. The parts may be readily adjusted in a simple manner to insure proper opening and closing, and all parts of the mechanism are easily accessible for adjustment, replacement and/or repair. An extremely valuable and important feature of the invention is the provision of means, including the headed pin 32, aperture adapted to be closed by the screw 42, and the latching and release bar 43, which permit ready actuation of the latch and actuating mechanism in emergencies during such times as the key 35 may be broken off in the lock.

It should be understood that it is not desired or intended to limit this invention to the exact details of construction or to the precise mode of use, herein shown and described, for various modifications within the scope of the appended claims may occur to persons skilled in the art to which this invention pertains.

I claim:

1. A closure lock and actuating mechanism comprising, a fixed support, a closure swingable about a pivotal axis relative to said support, a lock fixedly mounted relative to said support and having a laterally projecting arm swingable about the axis of rotation of the lock key, stop means associated with said support for limiting the movement of said arm, a link having one end connected to the swinging end of said arm and the other end associated with said closure remote from its pivotal axis to transmit motion from said arm to said closure, and means for swinging said arm and said link to a position wherein the swinging motion thereof is arrested by said stop means to positively prevent opening of said closure by externally applied pressure when the lock key is removed.

2. A closure lock and actuating mechanism comprising, a fixed support, a closure swingable about a pivotal axis relative to said support, a lock fixedly mounted relative to said support and having an arm swingable about the axis of rotation of the lock key, a link having one end connected to the swinging end of said arm, another link having an end connected to said closure remote from its pivotal axis, and a motion transfer lever having its medial portion pivotally mounted with respect to said support and having opposite swinging ends connected to the other ends of said links.

3. A closure lock and actuating mechanism comprising, a fixed support, a closure swingable about a pivotal axis relative to said support, a lock fixedly mounted relative to said support and

having an arm swingable about the axis of rotation of the lock key, a link having one end connected to the swinging end of said arm, another link having an end connected to said closure remote from its pivotal axis, and a motion transfer lever having its medial portion pivotally mounted with respect to said support and having opposite swinging ends connected to the other ends of said links, said arm and said first-mentioned link being swingable to a position wherein the swinging motion thereof is arrested to positively prevent opening of said closure by externally applied pressure when the lock key is removed.

4. A closure lock and actuating mechanism comprising, a fixed support, a closure, a support for said closure swingable about a pivotal axis relative to said fixed support, a lock fixedly mounted relative to said fixed support and having an arm swingable about the axis of rotation of the lock key, a link having one end connected to the swinging end of said arm, another link having an end connected to said closure support remote from its pivotal axis, and a motion transfer lever having its medial portion pivotally mounted with respect to said fixed support and having opposite swinging ends connected to the other ends of said links.

5. A closure lock and actuating mechanism comprising, a fixed support, a closure, a support for said closure pivotally suspended from said fixed support for swinging movement relative thereto, a lock secured to said fixed support and having an arm at its inner end swingable about the axis of rotation of the lock key, a link having one end connected to the swinging end of said arm, another link having an end connected to said closure support remote from its pivotal axis, and a motion transfer lever having its medial portion pivotally mounted on said fixed support and having opposite swinging ends connected to the other ends of said links.

6. A closure lock and actuating mechanism comprising, a fixed support, a closure swingable about a pivotal axis relative to said support, a lock fixedly mounted relative to said support and having an arm swingable about the axis of rotation of the lock key, a link having one end connected to the swinging end of said arm, another link having an end connected to said closure remote from its pivotal axis, and a motion transfer lever having its medial portion pivotally mounted with respect to said support and having opposite swinging ends connected to the other ends of said links, said links being adjustable in length to facilitate proper positioning of said closure.
